UNITED STATES PATENT OFFICE.

NICHOLAS ZUCK AND FRANK G. PFISTERER, OF ROCHESTER, NEW YORK.

FABRIC.

1,144,519.

Specification of Letters Patent.

Patented June 29, 1915.

Application filed October 3, 1914. Serial No. 864,755.

To all whom it may concern:

Be it known that we, NICHOLAS ZUCK and FRANK G. PFISTERER, of Rochester, in the county of Monroe and State of New York, ⁵ have invented certain new and useful Improvements in Fabric; and we do hereby declare the following to be a full, clear, and exact description of the same, reference being had to the accompanying drawings, ¹⁰ forming a part of this specification, and to the reference-numerals marked thereon.

The invention relates to fabrics, and more particularly to haircloth fabric such as employed for imparting stiffness to coats, garments and the like, and it has for its object ¹⁵ to afford a haircloth structure in which the hairs are held tightly and prevented from loosening, or from pulling away from the fabric.

²⁰ Another purpose of the invention is to provide a stiffening haircloth that is flexible and can be the more readily shaped to the garment to which it is applied, the fabric being constructed in such a manner as ²⁵ to cause it to retain the shape that is imparted.

To these and other ends the invention consists in certain improvements and combinations of parts all as will be hereinafter ³⁰ more fully described, the novel features being pointed out in the claims at the end of the specification.

In the drawings: Figure 1 is a plan view of a haircloth structure constructed in accordance with the invention, and Fig. 2 is a longitudinal section of the same.

Similar reference characters throughout the several figures indicate the same parts.

In haircloth fabrics as heretofore constructed, the hairs are arranged in juxtaposition to each other, affording a body that is too stiff and lacking in pliability to adjust itself readily to any particular shape, and a further disadvantage lies in the fact ⁴⁰ that the hairs quickly loosen and pull out, destroying the efficiency of the fabric as a whole. In the present invention, we overcome this by arranging the hairs in spaced relation to each other, rendering the fabric ⁴⁵ more pliable and more workable when applied to garments. In order to obviate loosening and pulling out of the hairs, we employ a suitable binder of cementitious or

equivalent substance that is applied to the fabric and forms a tight union between the ⁵⁵ hairs and the strands which hold them. The result of this is that each hair is held rigidly to the body of the fabric and while the hairs may possibly break off, they cannot loosen or become detached from the ⁶⁰ main structure.

In the present embodiment, A designates a series of hairs arranged in spaced relation to each other at about the relative distance shown, although it will be understood ⁶⁵ that the interval between the hairs may vary depending upon the use to which the fabric is to be put. B designates the securing strands or threads which may be of cotton or other material, and these are also ⁷⁰ arranged in spaced relation to each other. At one edge, a marginal portion C may be provided, formed by arranging a series of securing strands adjacent to each other and leaving the ends of the hairs A projecting beyond. Such a marginal portion ⁷⁵ is especially serviceable when the fabric is to be used as a stiffener for coat fronts, as the free ends of the hairs need not be trimmed until after the haircloth and the coat front are attached to the garment.

The hairs are caused to adhere to the securing strands fixedly by a suitable cementitious binding medium which may be applied in any convenient way. This we ⁸⁵ preferably accomplish by dipping the fabric in the substance that is employed, although other methods of impregnating the body of the fabric with a cementitious binder may be employed. The cement that ⁹⁰ is used may be of any character provided it is waterproof and stainless and capable of thoroughly permeating the interstices of the fabric, to effect a close adherence between the hairs and the securing strands. ⁹⁵

With this construction it is practically impossible to remove an entire hair from the fabric without damaging the fabric considerably, and the possibility of the hairs becoming loose and working out is rendered practically *nil*. The structure also affords a haircloth that is more inexpensive to manufacture than the usual form, and adjusts itself much more readily to any desired shape in constructing a garment than ¹⁰⁰ the usual closely woven haircloth. ¹⁰⁵

We claim as our invention:

1. A fabric embodying a series of hairs arranged in spaced relation to each other, the fabric being impregnated with a waterproof cementitious substance.

NICHOLAS ZUCK.

FRANK G. PFISTNER.

2. A fabric embodying a series of hairs arranged in spaced relation to each other and secured by threads or strands extending at angles to the hairs and also arranged in
